OIL WELL PACKER

Warren E. Scoville, Jr., Nutley, N. J., assignor to
United States Rubber Company, New York,
N. Y., a corporation of New Jersey

Application March 21, 1946, Serial No. 656,069

5 Claims. (Cl. 166—10)

1

This invention relates to oil well packers adapted to be lowered into a well and then expanded to shut off a portion of the well, and more particularly to the so-called compression type of packer in which a reinforced rubber sleeve mounted on a drill pipe or well tubing is adapted to be expanded by compressing the packer longitudinally.

Oil well packers of the type contemplated by the present invention are adapted to be expanded into sealing contact with the inside of a casing, or into sealing contact with the wall formation of the well when a casing is not in place. These packers when used in deep wells where they may be lowered to a depth of 5,000 to 10,000 feet or more are subjected to tremendous pressures during the well sealing period, and as constructed heretofore are short lived when used in deep wells.

The purpose in using rubber packers is to seal off a portion or portions of a well so that gas, water or other fluids present in such sealed-off area may be removed from the well for production or test purposes while excluding other fluids or gases. The rubber packer may, as above stated, be expanded to seal off a portion of the casing in the well or to engage the formation walls of the hole. It is this latter use in which the packer is expanded sufficiently to engage the formation walls of the hole with a sealing action that is most injurious to the packer.

In order to lower the packer assembly into the drill hole without undue difficulty caused by its touching the casing wall or swabbing the hole in the formation, certain allowance for clearance is usually provided for in designing the rubber packer. When a packer of the type herein contemplated is used in a portion of the well which does not contain a casing, it is lowered to the selected depth and then expanded laterally by a downward pressing force into sealing engagement with the formation of the walls of the hole. It is customary in rotary drilling to keep the hole filled with mud and water until the hole is cased. The weight of this long column of mud exerts a tremendous downward pressure upon the packer that tends to force the expanded outer walls of the packer downwardly about the supported lower head of the packer with shearing action. It has been attempted heretofore to resist this shearing force by reinforcing the packer with cord fabric and woven duck, and by wrapping the end portions of the packer with wire, but with the present day tendency of drilling wells deeper and deeper there is an urgent need

2

of packers that are stronger and more serviceable than those available heretofore.

The present invention therefore relates to the compression type of oil well packer which is so constructed that it is much better adapted to withstand the tremendous shearing forces to which it is likely to be subjected in use than the packers manufactured heretofore.

The increased strength and wearing properties of the packers of the present invention are secured by providing a metal head at each end of the body portion of the packer and by providing plies of cord fabric which surround this body throughout the central portion of its length but taper inwardly near each end where they are firmly anchored to the heads. In addition to this a number of metal rings are preferably provided near each head outside of the tapered portion of the cord fabric, and adjacent these metal rings are provided frustro-conical textile rings one of which fits in the space between the cord fabric and the metal rings and the other is positioned inside the tapered wall formed by the plies of cord fabric. The arrangement is such that at the time the well packer is subjected to the most severe downward forces tending to rupture the same, the reinforcing plies will be firmly gripped between and supported by the frustro-conical rings and these rings are supported by the surrounding metal rings. The reinforcing plies of cord fabric may be rubberized cord fabric cut on the bias much the same as in the construction of tire carcasses.

The above and other features of the present invention will be more fully understood from the following description when read in connection with the accompanying drawings; wherein

Fig. 1 is a vertical sectional view through the lower end portion of an oil well having the packer of the present invention positioned therein but not expanded.

Fig. 2 on a larger scale is a vertical sectional view of the packer of Fig. 1.

Fig. 3 shows the packer of Fig. 1 partly in full lines and partly in section and as expanded into sealing engagement with the formation walls of the hole; and

Fig. 4 is a sectional view taken on the lines 4—4 of Fig. 2.

The oil well shown in the drawing is not lined in that it is not provided with the usual metal casing that is frequently used, but the present packer may be used in lined wells. The side formation walls of the well are indicated by 10 and the bottom of this well is indicated by 11.

and the packer of the present invention is designated in its entirety by 12. The well is shown as having lowered therein the usual connected well pipes or tubings 13 and the lower end of this tubing is indicated by 14. The tubing 13 has slidably mounted thereupon the surrounding metal sleeve 15 and, the arrangement is such that the sleeve 15 may be slid longitudinally upon the lower end of the tubing 13 which extends downward from the upper end of the well and may be of great length. The tubing 13 is shown as having an outwardly extending pin 16 adapted to slide up and down in a J-shaped slot 16' formed in a wall of the sleeve 15. The tubing 13 has also a slot 17 through one wall and which may be brought into alignment with a hole 17' in a wall of the sleeve 15.

The parts are shown in Fig. 1 with the pin 16 at the top of the slot 16' so that the weight of the sleeve 15 is supported by the pin 16 through its engagement with the top of the slot 16'. When the parts are in this position the packer 12 is not expanded. To expand the packer 12 the parts are lowered in the well until a stop sleeve 18 attached to the lower end of the packer strikes the bottom 11 of the well, whereupon if the tubing 13 is lowered further its pin 16 will engage the bottom of the slot 16' and push downwardly on the sleeve 15 to expand the packer 12. When it is desired to admit fluid into the bore of the tubing 13 from exterior of the sleeve 15, the pin 16 is moved into engagement with the part 16'' of the slot 16'.

The mechanism described so far by reference numerals with the exception of the packer 12, is well known and forms no essential part of the present invention. The oil well packer 12 being of the compression type is adapted to be expanded by heavy pressure exerted upon the upper end of the packer by the downward movement of the sleeve 15 while the lower end of the packer is supported by the sleeve 18. In the construction shown the lower end 14 of the tubing 13 extends downwardly some distance into the stop sleeve 18 and this sleeve has a number of apertures 19 through which the fluid in the bottom of the well may pass into the interior of the sleeve. This sleeve 18 is provided at its upper end with an integral head-engaging flange 20, and the lower end of the sleeve 15 is provided with a similar integral flange 21. The packer 12 is, as above stated, expanded by lowering the sleeve 15 a few inches under the weight of the tubing 13 while the lower end of the packer is supported by the stop sleeve 18.

The oil well packer 12 which forms the subject matter of the present invention will now be described in detail and since it is designed to withstand pressures amounting to many tons without rupturing, its walls are thick and it is made very strong throughout. The packer as shown in the drawing comprises a tubular body 22 of vulcanized rubber and the inner bore of this tube and outer periphery thereof are reinforced with plies of cord fabric which may be very similar to the cord fabric used today in pneumatic automobile tires.

The reinforcing cord fabric used is a weftless fabric formed of rubberized cord, and wherever such reinforcing fabric is used two plies are employed so that the cords of one ply may be disposed diagonally to the longitudinal axis of the packer in one direction and the cords of the other ply disposed diagonally to the longitudinal axis of the packer in the opposite direction. This is

important in order that the cords may accommodate themselves to the bulging action of the packer as it is expanded from its cylindrical shape of Fig. 2 to the barrel shape of Fig. 3 where its side walls are expanded into sealing contact with the side walls 10 of the well hole. The thick tubular body 22 of rubber is reinforced adjacent its bore by the sheets of cord fabric 23 and this body 22 is reinforced at its outer periphery midway between its ends by several plies 24 of cord fabric. The packer 12 has the same construction at both ends so that if the lower end, which as will be presently pointed out is subjected to much more injurious forces than the upper end, becomes damaged the packer may be removed from the well and turned end for end for further use.

The packer 12 is formed at each end with what may be called a head and this head consists primarily of a heavy metal ring 25 having extending therefrom clamping bolts 26. These bolts are adapted to secure one end of the packer to the flange 20 and the other end to the flange 21, by means of the nuts 27.

When the packer 12 has been expanded as shown in Fig. 3 to seal off a portion of the well, thus separating the column of liquid mud 28 above the expanded packer 12 from a lower well section to be worked or tested, the packer may support a column of mud several thousand feet high which exerts a tremendous downward pressure upon the expanded packer. The effect of this is to subject the lower portion of the packer to a very severe shearing force as the weight of this column of mud tends to force the expanded portion of the packer downwardly about the head at the lower end of the packer. To enable the packer of the present invention to resist the destructive action of this downward pressure the following construction is employed. The reinforcing plies 24 extend throughout the length of the packer and are strengthened from near the central portion of the packer to the ends thereof by the additional plies of cord fabric 29. These plies 24 and 29 converge inwardly near each end of the packer so as to pass inside the metal ring 25 and are folded about such ring and extend outwardly in a horizontal direction as indicated at 30, to thereby firmly anchor these plies to the rings 25. At each end of the packer are provided a number of fabric discs 31 that rest against the laterally extending portion 30 of the reinforcing plies, and the clamping bolts 26 pass through holes in these discs. The rings 25 it will be noted are surrounded by rubber to thereby provide a cushion between the parts and also to bond the plies to this ring.

In order further to strengthen the end positions of the packer against severe outward and downward forces the plies 24 and 29 are internally reinforced above the ring 25 by the frustro-conical rings 32 and are externally reinforced by a second frustro-conical ring 33. These rings 32 and 33 are preferably formed of a heavy ribbon of fabric wound one coil about the other in the desired conical shape. The tremendous downward pressure which is exerted upon the expanded packer is further resisted, in accordance with the present invention, by providing about the ring 25 at each end of the packer a number of metal supporting rings 34 disposed one above the other as shown, so that when the conical rings 32 and 33 are distorted from the position in which they are shown in Fig. 2 to that in which they are shown in Fig. 3 they will be supported by the metal annulus formed of the rings 34.

All metal and fabric portions of the packer of the present invention are preferably surrounded by rubber as shown to provide a cushion action between the parts, and the bore of the packer and all exterior surfaces thereof are protected by a heavy film of rubber as indicated by 35. All rubber parts are properly vulcanized. Each of the head engaging flanges 20 and 21 is given the hollow construction shown so as to receive the end portion of the packer that is formed largely of the fabric discs 31.

It will be seen from the foregoing that the construction of the packer is such that when the clamping nuts 27 are tightened the ends of the reinforcing plies 24 and 29 will be subjected to a strong clamping action between the ring 25 and flange 20 or 21, and that a downward thrust exerted upon the packer by the weight of the column of mud 28 will be resisted by the cooperation of the rings 34 with the frusto-conical rings 32 and 33 between which the reinforcing plies 24 and 29 are gripped. In this manner an exceptionally strong and serviceable packer is provided.

Having thus described my invention, what I claim and desire to protect by Letters Patent is:

1. A well packer comprising, an expansible tubular body of elastic material, a metal ring at each end of said body, plies of cord fabric surrounding said body and firmly anchored to each ring, a semi-rigid frusto-conical textile ring surrounding the cord plies near each metal ring and formed of a number of heavy fabric plies wound one over the other to produce a ring that is rigid enough to retain the frusto-conical shape under expanded well closing conditions, and a metal annulus adjacent each metal ring positioned to support the adjacent semi-rigid frusto-conical ring to thereby support the expanded cord fabric near the metal rings against rupturing forces.

2. A well packer comprising, an expansible tubular body of elastic material, a metal ring at each end of said body, plies of cord fabric surrounding said body and firmly anchored to each ring, a semi-rigid frusto-conical textile ring surrounding the cord plies near each metal ring and formed of a number of heavy fabric plies wound one over the other to produce a ring that is rigid enough to retain the frusto-conical shape under expanded well closing conditions, and a metal annulus adjacent each metal ring and surrounding a portion of the adjacent frusto-conical ring, to thereby support the expanded cord fabric near the ends of the tubular body against rupturing forces.

3. A well packer comprising, an expansible tubular body of elastic material, a metal head at

each end of said body, plies of cord fabric surrounding said body and firmly anchored to each head, two semi-rigid frusto-conical rings disposed one at each side of said plies near each head each of these rings being formed of a number of fabric plies disposed one over the other to produce a ring that is rigid enough to retain its frusto-conical shape under expanded well closing conditions, and a metal annulus adjacent each head and positioned to support the adjacent frusto-conical rings to thereby support the expanded cord fabric near the ends of the tubular body against rupturing forces.

4. A well packer comprising, an expansible tubular body of elastic material, a metal head at each end of said body, plies of cord fabric surrounding said body throughout most of its length and inclined inward near each head and anchored to the head and formed of a number of heavy fabric plies wound one over the other to produce a ring that is rigid enough to retain the frusto-conical shape under expanded well closing conditions, a semi-rigid frusto-conical ring surrounding the inwardly inclined portion of said plies near each head, and a metal annulus adjacent each head and surrounding a portion of the adjacent frusto-conical ring to thereby support the plies near the ends of the tubular body against rupturing forces.

5. A well packer comprising, an expansible tubular body of elastic material, a metal ring at each end of said body, plies of cord fabric surrounding said body throughout most of its length and turned inwardly near each ring and folded about and anchored to the ring, a semi-rigid frusto-conical member surrounding the cord plies near each ring and formed of a number of heavy fabric plies wound one over the other to produce a ring that is rigid enough to retain its frusto-conical shape under expanded well closing conditions, and a metal annulus adjacent each ring and positioned to support the adjacent frusto-conical member to thereby support the expanded cord fabric near said rings against outward and downward forces.
